UNITED STATES PATENT OFFICE.

JOHN WEST, OF CHICAGO, ILLINOIS, ASSIGNOR TO BARNHART BROTHERS
& SPINDLER, OF SAME PLACE.

DESIGN FOR A FONT OF PRINTING-TYPE.

SPECIFICATION forming part of Design No. 20,750, dated May 19, 1891.

Application filed April 14, 1891. Serial No. 388,946. Term of patent 14 years.

To all whom it may concern:

Be it known that I, JOHN WEST, a citizen of the United States, residing at Chicago, county of Cook, and State of Illinois, have invented and produced a new and original Design for a Font of Printing-Type, which is fully set forth in the following specification, reference being had to the accompanying typographical impressions, forming a part thereof.

This design includes lower-case letters, capitals, figures, points, dollar-mark, and character &. In general character it is extended, quite ornamental, having heavy face with shade-lines. All terminal lines are concave at the end, and, with a few exceptions, are expanded at the end, the expansion in some instances, however, being scarcely more than a ceriph, but in most instances not being a true ceriph, but answering only to the description above given—viz., expanded and concave at the end. This character of line, which is not a true ceriph, is found in the lower end of lower-case a, tail of lower-case h, k, m, n, and w, the lower end of the stem of figure 7, initial stem of capital A, horizontal strokes of capitals E and F, lower end of final stroke of capital H, oblique lower stroke of capital K, horizontal stroke of capital L, tail of capital R, right-hand oblique stroke of capital Y, and both horizontal strokes of capital Z. Other like instances may be found. Lower-case f has the shade-line of the characteristic and of the end of the upper terminal of the stem blending with the shade-line of the body of the stem, making said shade-line continuous past the characteristic and terminal. Lower-case s has the upper extremity finished by an expansion which is substantially a ceriph and the lower extremity finished by a slight expansion only, the lower curve of S also being much more open than the upper curve, tangent to the former at the end, trending quite obliquely downward to the rear. The

lower-case t has the "cross-stroke" formed by a short triangular projection to the right from the stem, but not crossing said stem. Lower-case w has the first two elements curved at the bottom and the final element, consisting of a stem, extending below the line. The upper-curve element of capital B and the single-curve element of capitals D and R do not join the stem at the top, but terminate in an inwardly-tapering curve. Capital M is composed of two upwardly-curved elements having a common medial stem, while capital N, on the contrary, is angular.

The lower limit of the letters, both upper and lower case, and especially the lower-case, is irregular—that is to say, they do not terminate at any uniform line, nor do the elements which extend below the line extend equally below a uniform base-line. This is observable, for example, in lower-case b, in which the curve extends a little lower than the stem, and lower-case c, which, while not having an extension which would be conventionally termed "below the line," is, nevertheless, lower than any uniform line which could be taken as the general base-line of the font. Lower-case f extends a little below the line, but not so low as the tail of lower-case g, while the oblique terminal strokes of lower-case h and k are a little lower than f and not so low as the tail of g. These instances will suffice to illustrate this characteristic.

I claim—

The design for a font of printing-type herein shown and described.

In testimony whereof I have hereunto set my hand, at Chicago, Illinois, in the presence of two witness, this 25th day of March, 1891.

JOHN WEST.
